UNITED STATES PATENT OFFICE.

ARTHUR J. FILKINS, OF RIVERSIDE, ILLINOIS, ASSIGNOR TO PAUL DICKINSON
INCORPORATED, OF CHICAGO, ILLINOIS, A CORPORATION OF ILLINOIS.

SMOKE-JACK.

1,200,331.

Specification of Letters Patent.

Patented Oct. 3, 1916.

Application filed January 14, 1916. Serial No. 72,048.

To all whom it may concern:

Be it known that I, ARTHUR J. FILKINS, a citizen of the United States, residing at Riverside, in the county of Cook and State 5 of Illinois, have invented certain new and useful Improvements in Smoke-Jacks, of which the following is a specification.

This invention relates to smoke jacks or conduits for conveying the smoke from a 10 locomotive when placed in position in a roundhouse away from the interior of the roundhouse to the outer atmosphere.

The object of the invention, is to provide a smoke jack of the character described, 15 which shall be of improved construction and which shall be more convenient and effective in operation.

The invention is exemplified in the combination and arrangement of parts shown in 20 the accompanying drawings, described in the following specification, and it is more particularly pointed out in the appended claims.

In the drawings;—Figure 1, is a fragmentary sectional view through a portion of a roundhouse showing the smoke jack comprised in the present invention in side elevation. Fig. 2, is a detailed sectional view of a slide gate or valve used in connection with 25 the present invention. Fig. 3, is a fragmentary sectional view of a portion of a roundhouse taken at right angles to Fig. 1, and showing the smoke jack in elevation as viewed from the right in Fig. 1. Fig. 4, is a fragmentary detail of a portion of the support for the counterbalance used in connection with the invention.

In modern roundhouse construction, it is now the usual practice to provide a chimney 40 or stack located conveniently near the house proper, but, on a foundation independent of that of the building. A common conduit or smoke duct is positioned in the upper portion of the building, which is connected with the stack, and separate conduits or smoke jacks are provided for each stall or position 45 for the locomotives in the house and these jacks are all arranged to discharge into the main duct and to be connected with the smoke stacks of the locomotives when they 50 are in position in the house.

In the drawings, the numeral 1, designates the main smoke duct supported by timbers 2, near the upper portion of the

house. The duct 1, is provided with a 55 series of openings 3, one for each separate conduit or jack discharging into the duct, and each of these openings is provided with a slide gate or valve 4, mounted to slide in guides 5, for opening and closing the communicating passage between the jack and the main smoke duct. The valve 4, may be operated by any suitable means, a cable 6 being shown in the drawing for this purpose. A pipe section 7, is secured rigidly to 60 the frame of the opening 3, and extends laterally therefrom in practice a distance between two and one-half and three feet. The pipe itself, is made approximately two feet in diameter. Arranged to telescope with 65 the section 7, is a second pipe section 8, carried by hangers 9, suspended from a traveling roller 10. The roller 10, is mounted for movement on a trackway 11, supported by one of the timbers 12, of the roundhouse 70 building. A second roller 13 connected with the roller 10, by means of links 14, is also mounted for movement on the track 11. The pipe section 8, is provided at its end with a downwardly turned elbow 15, which 75 elbow is connected at its lower portion by means of a ball socket joint 16 with a pivoted depending pipe section 17, the two parts being connected by pivots 18.

Rigidly secured to the casing of the bell 80 joint 16, and extending laterally therefrom, is a bracket arm 19, connected by a link 20 with the pulley 13. The outer end of the bracket arm 19, is connected at 21, with a depending pivotal link 22, which is provided 85 with counterbalance arms 23, pivotally mounted at 24, at the lower end of the link. The pivot 24 forms a pivotal support or fulcrum member for the counterbalance arms. As shown in Fig. 3, the link 22, 90 has a pair of laterally extending forks 25, and a pair of counterbalance arms 23, one on each side of the pipe section, are provided. Each of the arms 23, is provided 95 with a forwardly extending segment 26, 100 having an arcuate grooved periphery 27, for receiving a chain 28, attached at its end to the upper portion of the segment, as shown at 29', in Fig. 1. Suspended by the chains 28, is a pipe section 29, having telescoping connection with the section 17, and provided at its lower end with a spherically-shaped casting 30, to which are se- 105

cured bales 31, carried at the ends of the chains 28. Suspended from the casting 30, by means of pivots 32, is a disk-shaped member 33, provided with a flat open bottom 34.

As shown best in Fig. 4 the pipe section 17 is connected with the lower end of the link 22 by means of a link 35 having one end pivotally secured to the fulcrum rod 24 and the other end pivotally secured at 36 to the pipe section. By this arrangement, the fulcrum member 24, of the counterbalance arms 23, is always maintained at a fixed distance from its pivotal connection 15 with the pipe section 17. It will be apparent that the entire pivotally suspended portion of the smoke jack may be swung about its pivot 18 in either direction, as indicated in broken lines, in Fig. 1, and that the fulcrum 24 and the counterbalance arm carried thereby, will be swung in unison with the depending pipe section. Weights 37, are carried at the ends of the arms 23 and are of the proper size to accurately counterbalance the telescoping section 29 of the depending pipe section, together with the parts carried thereby. By this arrangement, the telescoping section 29, may be raised or lowered relative to the section 17, 20 and will be retained in whatever position it is moved into, the friction on the pivotal support 24, being sufficient to prevent accidental displacement. The adjustment of the section 29, is effected by a depending rope 35 or cord 38, having one end attached to the arm 23, and a laterally extending rod on the other end similarly secured to the periphery 27, of the counterbalance segment 26. The entire structure supported by the rollers 10 and 13, is adjustable back and forth, toward and away from the main smoke duct 1, the adjustment being accomplished by means 40 of a cable 39, which passes over a fixed pulley 40, secured to the timber 12, and which 45 has its ends carried over guide pulleys 41, to a windlass 42, located at a point convenient for operation. The lower run of the upper portion of the cable 39, is secured to an upwardly projecting lug 39', 50 fastened to the movable section 8 of the horizontal extending portion of the smoke conduit, so that any movement of the cable 39, will cause this section to be telescoped in and out of the fixed section 7. The windlass 42, is driven by a hand crank 43, which 55 may be turned in either direction to shift the smoke jack toward or away from the main smoke duct 1.

The operation of the device is as follows: 60 The telescoping sections 29, of the various jacks in the roundhouse will ordinarily be left raised to a position somewhat above the level of the upper end of a locomotive smoke stack, indicated in broken lines, at 45. When 65 an engine is run into the roundhouse, it will

be stopped with its stack approximately beneath the lower end of the jack. It is, of course, quite difficult to stop the engine exactly beneath a fixed jack, and for this reason, the applicant has provided the means 70 for adjusting his jack longitudinally of the direction of movement of the engine in entering the roundhouse. After the engine has come to a standstill, the hand crank 43, will be rotated in the proper direction to 75 bring the swinging connecting member 33, directly over the upper end of the engine smoke stack, and the cord 38 will then be operated to lower the connection 33 and the telescoping section 29, until the connection 80 rests in the upper end of the engine stack. The slide valve 4, will in the meantime be opened to connect the jack with the main smoke duct and the escaping products of combustion from the engine will be carried 85 upwardly through the jack into the smoke duct and thence to the chimney with which the smoke duct is connected. When it is desired to remove the engine from the roundhouse, the lower end of the smoke jack may 90 be raised from the top of the engine stack and the engine driven from the house. It may sometimes happen, however, that the attendants will forget or neglect to raise the jack before the engine is started. In this 95 case, with the old form of jacks, it has frequently happened that the jack itself is either bent or broken. With the present form, however, this is impossible, for the reason that if the engine is moved while the 100 lower end of the jack is still in contact with the engine stack, the jack will merely be swung slightly in the direction of movement of the engine, as indicated in broken lines, in Fig. 1, until it reaches a position where it 105 clears the upper end of the stack and the engine will continue to move outwardly without doing any damage. Of course, it will be understood that the telescoping adjustment of the members 7 and 8 of the jack 110 could be dispensed with and the depending pivotal portion be swung about its pivot 18, to bring it into position over the top of the locomotive stack. It has been found in practice, however, to be desirable to provide the 115 jack with both adjustments. When a particular jack is not in use, the valve 4 is left closed to prevent any inrush of air through an idle jack, due to the draft in the main stack or chimney. When a cold engine is 120 being fired, it is of very material assistance to be able to connect the stack of the engine with the draft in the main chimney through the smoke duct 1 and the smoke jack, thus creating a forced draft in the 125 engine to assist in starting fires.

All of the parts of the jack, together with the main smoke duct 1, are preferably made of cast iron, since this material resists the action of the corrosive elements in the prod- 130

ucts of combustion from the engine furnace much more effectively, than other metals, such as wrought iron or steel.

Having thus described my invention, what I claim as new and desire to secure by United States Letters Patent is:—

1. In combination, a smoke outlet, a conduit having a horizontal telescoping section for conducting smoke to said outlet, a smoke receiver connected with said telescoping section, and means for moving said section telescopically to position said receiver.

2. In a device of the character described, a smoke conduit having a horizontal telescoping section, a depending receiving portion pivotally connected with said section, and means for telescopically adjusting said horizontal section to position said receiving portion.

3. In a device of the character described, a smoke jack comprising a fixed horizontal pipe section; a movable horizontal pipe section arranged to telescope with said fixed section; a depending pipe section connected with said movable section; and means for telescoping said movable section with said fixed section to adjust the position of the lower receiving end of said depending section.

4. In a device of the character described, a smoke jack comprising a horizontally adjustable outlet portion; and a depending telescoping receiving portion pivotally supported by said outlet portion for swinging movement about a horizontal axis.

5. In a device of the character described, a smoke jack comprising a horizontal telescoping section; a movable carriage for supporting said section; a smoke receiving portion carried by said section; and means for moving said section and carriage to adjust the position of said smoke receiving portion.

6. In a device of the character described, a smoke jack having a horizontal telescoping section; a carriage and runway for supporting said section; a smoke receiving portion carried by said section; and a cable secured to said section and arranged to move said section and carriage in a horizontal direction to adjust the position of said receiving portion.

7. In a device of the character described, a main smoke duct; a conduit communicating with said duct and provided with fixed and movable horizontally telescoping sections; a smoke receiving portion carried by a movable section of said conduit; and means for telescoping said movable section relative to said fixed section to adjust the position of said smoke receiving portion.

8. In a device of the character described, a main smoke duct; a smoke jack connected with said duct and provided with fixed and movable horizontally telescoping sections; a smoke receiving portion connected with a

movable section of said jack; means for telescoping said sections relative to one another to adjust the position of said smoke receiving portion; and a valve for closing the communication between said jack and said main smoke duct.

9. In a device of the character described, a smoke jack having a vertically adjustable depending smoke receiving section; a counterbalance for holding said section in adjusted positions; and a movable fulcrum for said counterbalance and means for retaining said fulcrum in fixed operative relation to said section.

10. In a device of the character described, a smoke jack having a vertically adjustable smoke receiving section; means for pivotally supporting said section for movement about a horizontal axis; a counterbalance for said section; a fulcrum for said counterbalance; and means for supporting said fulcrum for movement in a horizontal direction in unison with said section.

11. In a device of the character described, a pivotally supported smoke receiving section; a counterbalance for said section; a fulcrum for said counterbalance; and a pivotally supported depending link for supporting said fulcrum.

12. In a device of the character described, a smoke jack having a depending smoke receiving section pivotally supported at its upper end; and provided at its lower end with a spherically shaped terminal portion having a bowl-shaped connection member pivotally swung from said portion and held by gravity in position to form connection with the upper end of a locomotive smoke stack, regardless of the positions of said section on its pivotal support.

13. In combination, a smoke jack comprising a pivotally supported depending pipe section; a second pipe section arranged to telescope with said first mentioned section and having a spherically shaped terminal portion; and a bowl-shaped swinging hood or connection member pivotally supported by said terminal portion and arranged to be held in position by gravity for connection with the upper end of a locomotive smoke stack regardless of the positions of said sections on their pivotal support.

14. In combination, a smoke jack comprising a depending pivotally supported pipe section; a second pipe section arranged to telescope with said first mentioned section; a counterbalance connected with said telescoping section for holding said sections in adjusted positions; a movable fulcrum for said counterbalance; and a swinging connecting hood carried by said telescoping section.

15. In combination, a smoke jack comprising a horizontally telescoping section; a vertically telescoping section connected

with said horizontally telescoping section and means for telescopically moving the parts of one of said sections relative to one another to adjust the length of said section.

5 16. In combination, a smoke jack comprising a horizontally telescoping section; a vertically telescoping section pivotally carried by said horizontally telescoping section and means for telescopically moving the 10 parts of one of said sections relative to one another to adjust the length of said section.

15 17. In combination, a smoke jack comprising horizontally telescoping sections; a depending vertically telescoping section pivotally supported from a horizontally telescoping section; and provided at its lower end with a swinging connection member for connecting said jack with the upper end of a locomotive stack.

20 18. In a device of the character described, a main smoke duct; a smoke jack having an outlet into said duct; a valve for opening and closing said outlet; horizontally telescoping pipe sections forming a portion of said smoke jack; vertically telescoping pipe sections connected with a horizontally telescoping section; means for connecting said vertically telescoping section with a locomotive

30 stack; and means for adjusting said horizontally telescoping sections relative to one another to position said vertically telescoping sections over said locomotive stack.

35 19. In a device of the character described, a main smoke duct; a smoke jack communicating with said duct and comprising horizontally telescoping sections and depending vertically telescoping sections; a counterbalance for said depending sections; means for connecting the lower one to said depending sections with the upper end of a locomotive stack; and a pivotal connection between said depending sections and said horizontally adjustable sections to permit movement of said depending sections independently of said horizontally telescoping sections.

40 45 In testimony whereof I have signed my name to this specification, in the presence of two subscribing witnesses, on this 7th day of January, A. D. 1916.
